ATTORNEY.

UNITED STATES PATENT OFFICE.

CLYDE L. GIBBENS, OF MADISON, WISCONSIN.

SHOE-POLISHER.

1,330,313.

Specification of Letters Patent. Patented Feb. 10, 1920.

Application filed July 19, 1919. Serial No. 311,932.

To all whom it may concern:

Be it known that I, CLYDE L. GIBBENS, a citizen of the United States, residing at Madison, in the county of Dane and State 5 of Wisconsin, have invented new and useful Improvements in Shoe-Polishers, of which the following is a specification.

This invention comprehends the provision of a shoe polishing device and embodies 10 among other features, a frame, and a length of cloth adapted to be secured to the opposite ends of the frame, the latter constituting a handle for the device.

In carrying out the invention, I construct 15 the frame of sections capable of being compactly folded, so that the device will occupy a minimum of space when not in use.

The nature and advantages of the invention will be better understood when the following detail description is taken in connection with the accompanying drawings, 20 the invention residing in the construction, combination and arrangement of parts as claimed.

25 In the drawings forming part of this specification, like numerals of reference indicate similar parts in the several views and wherein:

Figure 1 is a side elevation of the device 30 showing the parts in position for use.

Fig. 2 is a top plan view.

Fig. 3 is a view showing the frame of the device folded.

The device forming the subject matter of 35 my invention embodies a frame indicated generally at A, and a length of cloth indicated at B. The frame may be constructed from any suitable material, preferably wire, and embodies an intermediate section 40 10 of elongated rectangular formation, and end section 11 and 12 respectively. The end sections are also of elongated rectangular formation, and each has its parallel limbs coiled to provide aligned eyes 13 which loosely 45 embrace the adjacent ends of the intermediate section 10. The ends 10 of the intermediate section 10 constitute pivots upon which the end sections 11 and 12 respectively are movable. The eyes 13 terminate to provide 50 hooks 15 which are adapted to engage the parallel sides of the intermediate section

10 when the parts are in position for use. The hooks 15 hold the end sections 11 and 12 respectively extended from the intermediate section 10 at the proper inclination 55 with respect thereto as shown in Fig. 1. The length of cloth B constituting the polishing element may be detachably secured to the outer ends of the sections 10 and 11 in any suitable manner. However, as 60 shown in this specific instance, the cloth B has its opposite ends folded over the adjacent ends of the respective sections 10 and 11 and a tooth like clamping element 17 which is slidably mounted upon each of the 65 sections 10 and 11 is brought into engagement with the free terminals of the cloth for holding the latter stretched upon the frame. The cloth can be readily and easily 70 adjusted from time to time to compensate for the stretching of the material, by loosening the clamping element as will be readily understood.

In practice, the parts are arranged in the manner shown in Fig. 1, whereupon the intermediate section 10 constitutes a handle for the device to facilitate the rubbing or moving of the cloth over the shoe to be polished. When use of the device is not desired, the end sections 11 and 12 respectively 75 may be readily and easily swung upon their pivots into superposed relation upon the intermediate section 10 as shown in Fig. 3. With the frame thus folded into compact form, it may be arranged conveniently in a 80 drawer, in a suit case or any other place, as it occupies a minimum space. The cloth B may be removed from the frame prior to folding the latter or the adjusting elements 85 can be arranged to permit of a slack in the cloth so that the latter may be folded with the frame.

While I have shown and described what I consider the preferred embodiment of the invention, I desire to have it understood 95 that I do not limit myself in this connection, inasmuch as such changes may be resorted to when desired as fall within the scope of what is claimed.

What I claim is:

In a device of the class described, a frame including an intermediate section, end sec-

tions pivotally mounted upon the opposite extremities of said intermediate section, said end sections being capable of being folded upon said intermediate section, hook like extremities formed on the end sections and adapted to engage the opposite sides of the intermediate section for holding the end sec-

tion at an inclination with respect to said intermediate section, a flexible element, and means for detachably securing the ends of said element to the end sections of the frame. 10

In testimony whereof I affix my signature.

CLYDE L. GIBBENS.
